Attorney.

UNITED STATES PATENT OFFICE.

THOMAS H. BENNETT, OF IRONTON, OHIO, ASSIGNOR OF TWO-THIRDS TO D. LINN GOUGH, OF SAME PLACE, AND A. L. STOUT, OF DAYTON, OHIO.

PUDDLING AND HEATING FURNACE.

SPECIFICATION forming part of Letters Patent No. 311,802, dated February 3, 1885.

Application filed March 7, 1884. (No model.)

To all whom it may concern:

Be it known that I, THOMAS H. BENNETT, a citizen of the United States, residing at Iron-ton, in the county of Lawrence and State of 5 Ohio, have invented certain new and useful Improvements in Puddling and Heating Furnaces, of which the following is a specification.

My invention relates to improvements in furnaces for puddling or heating iron; and the 10 objects of my improvements are, first, to economize fuel in the processes of puddling and of heating iron; second, to so thoroughly fuse the flue-cinder that it shall readily flow off when tapped; third, to cause a more powerful 15 draft through the furnace, and, fourth, to prevent the passing off of black smoke and offensive gases by the chimney. I attain these objects by means of the furnace illustrated in the accompanying drawings, in which—

20 Figure 1 is a vertical longitudinal section of a puddling-furnace embodying my improvements. Fig. 2 is a top view of the same. Fig. 3 is a transverse vertical section through line L M, Fig. 2; and Fig. 4 is a face and edge view 25 of a single brick with an air-hole through it.

Similar letters refer to similar parts throughout the several views.

A A are air holes or passages made through 30 bricks in the crown of the furnace. B is the neck of the furnace. C is the tap-hole for flue-cinder. D is the stoke-hole. E is the fire-grate. F is the ash-pit. G is the fire-bridge. H is the flue-bridge. I is the charging-door. J is the chimney or flue. K is the crown of 35 the furnace.

I build this furnace of the materials, dimensions, and designs in use for other puddling-furnaces; but I make one or more air-passages, A A, through its crown K, and leading from 40 the outer air into the neck B of the furnace. To make these air-passages A A, I use the brick illustrated by Fig. 4, having a hole, A', through it from one bed-face to the other. I lay these brick on end in longitudinal courses, as shown 45 in Fig. 1, so that their air-holes A' form a continuous air-passage, A A, from the front of the furnace to the beginning of the neck B, as shown in Figs. 1 and 2.

I have shown two air-passages, A A, Figs. 2 50 and 3; but I use one or two or more, according

to circumstances. I find it desirable to make my perforated brick longer than the ordinary brick used for building the crown of a puddling-furnace. So, when the ordinary brick are nine inches long, I make my perforated brick about twelve inches long, so as not to weaken the crown K in any manner. I find one inch and a half a suitable diameter for hole A'; but it may be made larger or smaller, provided it gives air-passages capable of admitting the quantity of air required. I use a slide-valve at the outer end of the air-passages A A to close, open, or partly open the air-passages A A, as may be desired. I have not shown this slide in the drawings, as it is a well-known device, and is easily applied. It will be observed that these flues receive air at the front only of the furnace, and not at a point between its front and rear extremities. It will also be noted that these air-passages are located directly over the fuel-chamber and the heating-chamber of the furnace, and that they extend in an unbroken line from the front of the former to the rear of the latter. It will also be perceived that the heated currents are discharged not into the fuel-chamber, or into the heating-chamber, or into the flue above the bridge-wall, but are delivered at a point behind all these. It will further be observed that the currents pass in a practically direct line from 55 the extreme front of the furnace to the rear of the puddling or heating chamber without deflecting or retarding angles, and that at their point of discharge into the neck they do not operate to obstruct or turn aside the currents 60 from the puddling-chamber to the chimney, but, flowing in the same direction and mingling with such currents, their added oxygen contributes to intensify the combustion, thereby consuming all carbonaceous substances and 65 greatly accelerating the draft. This construction, it will be seen, is quite distinct, both in purpose and effect, from that in which air is received unheated and by a downward discharge into the neck of the furnace.

This furnace is started and worked like other puddling-furnaces; but when a fire is kindled in it a draft is developed in chimney J, and crown K is heated to a high temperature. The draft in chimney J draws air through the 70 75 80 85 90 95 100

passages A A from the outer air into neck B, and this air gets heated while passing through the hot brick. When this hot air enters neck B it mixes with the flame and hot gases passing off from the furnace, and its oxygen combines with and burns up all unconsumed carbon and combustible gases it meets. This combustion intensifies the heat in the neck B to such a degree that the flue-cinder is thoroughly fused, and can be run off by tapping; also, the gases pass from the neck B at so high a temperature that they give a powerful draft in chimney J, and this gives a greater draft through the furnace and fire-grate E, which burns up the coal completely, and so prevents the loss of fuel incident to the raking of the fire when the draft is bad. As the flue-cinder is thoroughly fused in neck B and can be tapped off through hole C, the labor and the injury to the furnace incident to the removal of the flue-cinder when solidified or viscid are avoided, and the formation of "tea-cups" is rendered impossible; also, as the carbon, which, mixed with the chimney gases, forms black smoke, is burned in neck B, no such smoke passes off by the chimney; but all the carbon and gases being burned in neck B, the gases that pass off by the chimney are as harmless and inoffensive as the gases of combustion can be. The quantity of air passed through the passages A A may, if desired, be increased to an indefinite extent by connecting them with

any blowing apparatus; but the method of so connecting them is obvious and need not be specified.

What I claim as my invention, and desire to secure by Letters Patent, is—

1. In a furnace for puddling or heating, the combination, with the fuel and puddling chambers, of an air-passage, A A, within the crown of the furnace, extending from the front of the fuel-chamber to the rear of the puddling-chamber, and discharging into the front of the neck, substantially as described. 35

2. In a puddling or heating furnace, an air passage or flue, A A, extending from the front of the furnace along the crown thereof to the rear of the puddling-chamber, such flue being composed of a series of sections, A, placed face to face, and each provided with a single perforation, as described. 40

3. In a furnace, one or more air-flues, A A, extending along the crown of the furnace from the front of the same to the rear of the heating-chamber, and discharging into the front portion of the neck of the furnace, the upper portion of the neck constituting a continuation substantially in the same downwardly and rearwardly inclined plane of the upper portion of such flues, substantially as described. 50

THOMAS H. BENNETT.
